UNITED STATES PATENT OFFICE

CHARLES H. TALLMADGE, OF BUFFALO, NEW YORK, ASSIGNOR TO LYNN A. WILLIAMS,
OF CHICAGO, ILLINOIS

CARD FOR NUMERICAL CODING

Application filed April 10, 1924. Serial No. 705,697.

My invention relates to a system or method of numerical coding by means of which all the easier natural numbers are equally distributed throughout nine or more great groups, and to the method of mechanically controlling the sorting of punched cards, the filing of documents, the routing of telephone communications and generally similar operations according to such novel method of coding which may be described as characterized by a left-hand lineup.

One of the objects of the invention is to increase the practical capacity of a qualitative field of two or more columns.

Another object of the invention is to increase the numbers in a code, thereby reducing the time and labor of punching the holes in record cards, and the likelihood to error in such punching.

A further object of the invention is to reduce the time and labor required in sorting the cards and the likelihood to pile or multilate them in the sorting operation.

Another object of the invention is to permit the freer use of the smaller numbers of a given code without the carding and sorting handicap for such numbers, namely, the carding of such numbers by punching two, three or four holes instead of five and the sorting of them in two, three or four runnings instead of five.

A still further object is to distribute such small, better numbers equally among the conventional ten groups of a coding classification instead of concentrating them all in one group.

Other objects and advantages will appear in the further description of the invention.

Figure 1 is a vertical longitudinal section of a representative tabulating card sorting machine. Figure 2 is a vertical transverse section roughly on the line 2—2 of Figure 1 showing the adjustable spring contact.

Figure 3 shows a perforated record card of the kind adapted to be sorted by the machine punched according to my invention.

Figures 4 to 13 inclusive show portions of cards similar to that shown in Figure 3.

One use of my method is perhaps most easily visualized by illustration from the me-

chanical card tabulating art, in which the data to be tabulated are transferred to punched cards, certain quantitative data in a field or fields of their own, to be summed, and other preliminary classificational data, such as office number, or serial number, or account number, in other appropriate fields.

In a well considered classification scheme the several groups have important, less important and relatively unimportant classes of many grades, and efficient coding will attempt to assign the best number in each group to the most active class, the second-best numbers to classes of secondary importance, etc.

Obviously, a system that puts the several groups on a basis of approximate equality as to best numbers is more desirable and efficient than one that crowds all the best numbers into one group to the exclusion of the others.

Ordinary right-hand lineup grouping does the latter, when it does not altogether ignore the smaller numbers. Left-hand lineup grouping equalizes the distribution of the smaller numbers among the groups and utilizes all the best numbers, thereby increasing the economy of mechanical sorting and the efficiency of mechanical tabulation.

Before making any analytical summation of values or quantities, the cards are commonly run through a sorting device to separate them into groups and sub-groups according to the numerical code adopted for the particular classification in hand.

In some lines of heavy coding, typically represented by the Import Schedule in Foreign Trade, the present method separates and distinguishes its main groups according to the conventional numerical order, throwing numbers 1, 2, 3, 5, 6, 8, and 10, 23, 99 and 123, 456 and 789, and, in fact all natural numbers below ten thousand into group 0, and preceding them by a punched cipher or ciphers in the case of a code with, say, five figures or columns. These ciphers must be sorted separately from the following significant figures by a separate running of the cards, one running for each column begin-

55

ning at the left, whether occupied by a cipher or not.

The present invention is based on the acceptance of a novel organization of all the great groups of numbers by initial figures, 5 whether the number is composed of one, two, three or more figures, thus throwing the above illustrative numbers into the following groups

1	2	3	456	5	6	789	8	99
10		23						
10 123								

Stated in other words, the natural numerical series 1 to 99,999, when grouped according to the conventional numerical consecution of the prior art falls into ten groups, of 15 which the first is 0, containing, let us say, all the one-, two-, three- and four-figure numbers up to 9,999; the second contains all five-figure numbers with initial 1. . . . ; the 20 third contains all five-figure numbers with initial 2. . . . and the tenth all five-figure numbers with initial 9. . . .

But the 9,999 numbers of one, two, three or four figures in the first group of the old 25 art are the very best of the whole series, and they may be equally divided into nine new groups of the present invention, of varying makeup as to actual numerical value, with the nine digits as initial figures, much the 30 same as the 90,000 five-figure numbers are now most naturally grouped according to their initial figures.

The left-hand lineup system of the present invention thus merely, but novelly and use- 35 fully, extends this initial-figure grouping to the numbers below, say 10,000, and combines such small numbers with the larger five-figure numbers already so grouped. It thereby es- 40 tablishes nine new great groups which share equally in the best (smaller) numbers, with practical advantages to be argued elsewhere but which must be thoroughly visualized in practice to be fully appreciated.

With the inclusion of a tenth group, dis- 45 tinguished from the other nine by having an initial 0, followed by 00 (or 01) to 09, 000 (001) to 099, 0000 (or 0001) to 0999, etc. (and the optional adoption of 0, 00, 000, 0000, etc. as class numbers), the full code of the new 50 invention would consist of the following preferred numbers:

1st preferred, one-figure	10 numbers (1 to 0, inc.)
2nd preferred, two-figure	110 numbers
3rd preferred, three-figure	1,100 numbers
4th preferred, four-figure	11,000 numbers
55 a total, say, of preferred numbers	12,220
and, say, common numbers of five-figures	110,000
or a grand total (five-column) capacity of	122,220 numbers

60 In theory the entire code would be available for the same number of classes, but in practice only a somewhat smaller number of assignments would be practicable in order to permit the best grouping of offices, accounts, 65 commodities, or the like classification, in such

a way as to adapt them to the rather inflexible code groups and the more or less varying and flexible classification groups. But few codes will have anything approaching this number of classes without expediently going into the sixth column, and with any 70 code having decidedly less demand for capacity, the better numbers would be the ones most likely to be used.

To consider more carefully the card-punching and tabulating art: 75

In typical quantitative fields the conventional rule of right-hand lineup is, of course, necessary in order that units may be added to units, etc.; but in the preliminary punching and sorting of the cards into classification groups, the prior art practice of units under units is merely a conventional routine carried over along the line of least resistance by a natural but unsound analogy from the summation work. In such classificational fields there is commonly no end to be served by a summation; or, if a summation is made, it is merely for the purpose of checking or auditing, with little or no other significance attached to the numerical value of the total, and for such purposes the new left-hand lineup total is quite as desirable as the conventional kind.

Certain phases of the art, however, disclose serious handicaps in using the old right-hand lineup in handling codes extending into three or more figures, the handicap becoming greater as the total capacity of the code increases to four or more figures. I have discovered that the adoption of the new left-hand lineup will remove these handicaps.

In practicing my invention in its simplest aspects, the several columns of the qualitative fields have no general units-tens-hundreds significance, but the rule is first figure first column, meaning in each case the first one counting from the left.

Other things being equal, small numbers are better for code work than large ones, but in the prior art method of punching a best number, as 1, in a five-place code, it must be preceded by four ciphers, thus, 00001, and it must then typically be sorted five times, once for each column, beginning at the left. Recognizing this handicap, the post-office code ignores all numbers with less than five places, and codes the main office of the country, for example, New York main office, 20,000, punching it 2X---, and sorting it only twice, the X hole in this case substituting for the four ciphers following the 2 in the first column. Thus, in the old art it is seen that for conventional carding and sorting the number 20,000 is better than the simpler and generally easier number 2. Somewhat similarly, though not so wisely, Chicago is coded 10,100, punched 101X--- and sorted four times. Each dash in these cases indicates the saving of a sorting. In the prior art methods, the 115 120 125 130

numbers with four, three or two terminal ciphers thus become substantially preferred over the others in card work, since for such preferred numbers the holes punched and the 5 cards run once in sorting may be reduced by 60, 40 and 20 percent respectively of the routine requirements.

In the left-hand lineup method, Chicago might be coded plain 1, and New York plain 2, 10 with seven other principal offices coded from 3 to 9, and they would be carded 1x - - -, 2x - - -, etc., and each one sorted only twice. Other principal offices would be coded 10, 15, 20, 99, 100, 1230, etc., and they would be 15 carded as written, with the X following the full number including any terminal cipher or ciphers in case the full number did not have the field limit of figures.

It does not seem practicable with the prior 20 art methods, with the right-hand lineup and its fixed units-tens-hundreds limitations, to use the left-hand columns of a large field wholly independent of the right-hand columns, but in practicing my invention it be- 25 comes quite feasible to do so.

It is thus practicable to have a total code 30 capacity running into six or eight columns, if desirable for occasional minute sub-classifications, and still confine the main classes in more active use to the two, three or four columns at the left without handicapping the carding or the sorting of the more desirable small numbers. This cannot be done with the prior art code methods.

35 An extensive comparative analysis of the system of my invention with the old systems would be too bulky to include in this specification, but such an analysis may be summarized as follows:

40 In the prior method, the Post Office code has a total capacity of 108,000 numbers with its two prefix series, against a corresponding total of 119,997 in the new art of my invention, and these two capacities may be ana- 45 lyzed item by item as follows:

First preferred: 9 two-run numbers in each art, with this difference: those of my new method are one-figure numbers while those of the old art are five-figured.

50 Second preferred: New method, 108 three-run numbers against old art 99. The new method numbers are two-figured—those of the old art are five-figured.

55 Third preferred: New method, 1080 four-run, three-figure numbers against old art 972 four-run, five-figure numbers.

60 This completes all that are commonly considered preferred in the old art, and the three preferences may be summarized as follows:

65 New method 1197 numbers against old art 1080, an increase of 117 numbers or 11 percent. The new method numbers require 3465 figures for a single writing while the same number 65 of numbers in the old art would require 5985

figures, a difference of 2520 figures or 42 percent of the old art requirement.

But this new method has a further (say fifth) set of preferred numbers against which the old art has nothing to offer. They are 70 10,800 numbers which are written with four figures, though requiring five holes to be punched and also requiring, superficially, five runs in sorting. In the writing of these 10,800 numbers there is a saving of 20 percent in figures over the same number of numbers in the old art.

75 In accounting and statistical work, it is not uncommon for some classes to be several hundred times as active as others, and where the disparity in activity is marked, it is important that the several economies in writing, carding and sorting class numbers, especially the principal ones, should co-operate instead of conflict as they do in the prior art. This 80 co-operation is secured by the left-hand lineup.

85 It is thus apparent that while the smaller numbers of the natural series, say the one-, two-, three- and four-figure numbers in the 90 series 1 to 99,999, are the best and most easily handled in all ordinary respects, there is a heavy handicap in the prior art in the carding and sorting of these numbers as compared with the carding and sorting of five-figure numbers which have two or more terminal ciphers, and which employ the X skip-bar as a substitute for such ciphers.

95 This handicap seems to have been responsible for the entire omission from the post-office code of any of the natural numbers of four figures or less, in spite of the obvious great advantages of such numbers for general purposes.

100 In my invention, this very useful X skip is employed even more freely than in the prior art methods, but with wholly different reading and sorting significances, and, as one of the results, the heavy handicap above referred to is removed.

105 In the prior methods, the advantage of this use of X comes partly from reducing the number of holes to be punched, but more from its sorting function by indicating that the unpunched columns at the right are 110 really cipher columns. The punching of the extra holes thus saved would not be so laborious nor attended by so much delay and other wastes as the running of the cards for the extra sortings.

115 In the new method, the saving of punchings is even greater, but it arises in a different manner. The old methods cannot save the punching of holes for a variable number of places preceding the significant figures of the columns actually needed for the use of small numbers like 1, 23, 456, etc., in a five-place code. In practice, it must precede them by something to fill the extra columns, and this something must be volition-

ally graduated and laboriously inserted, step by step. It does not seem practicable to utilize the skip-bar for this purpose. But by adopting the left-hand lineup, it is practicable to write the necessary figures first and then follow them more mechanically, however variably, by the skip-bar which has its terminal limit automatically set for the first column of the next field, whether it be one, 10 two or more columns away.

In the more important economy of sorting, as also in the lesser economy of punching, the new method saves by making available not merely an increased number of preferred ratings, as well as an increased total capacity with a given column limit, as will appear later, but by facilitating the assignment of such preferred ratings to active classes in greater ratio than the prior right-hand lineup methods can do, because such preferred numbers are distributed over all the groups instead of being principally confined to one group.

In a well considered classification scheme, 25 each of the several groups has important, less important and relatively unimportant classes of many grades, and efficient coding will attempt to assign the best number in each group to the most active class, the second-best numbers to classes of secondary importance, etc. The total advantage in punching and in sorting is the product of the single-use economy by the activity of the class.

Obviously, a system that puts the several 35 groups on a basis of approximate equality as to best numbers is more desirable and efficient than one that crowds all the best numbers into one group to the exclusion of the other groups. Ordinary right-hand grouping does the latter, when it does not altogether ignore the smaller numbers. Left-hand lineup grouping equalizes the distribution of the smaller numbers among the groups and permits a better utilization of the best numbers in the scheme, thereby increasing the economy of mechanical sorting and the efficiency of mechanical tabulation.

On the new method cards, 10,000 is written with the four ciphers, while on the old method 50 cards it is written 1x ---. This might seem to be merely a transfer of the valuable skip-bar function from the number 10,000 to the number 1, which would be a worthy accomplishment in itself, since it removes the 55 discrimination against the best of numbers, but further consideration reveals the further important fact: The left-hand lineup, with the transference of the skip-bar function of X from being a substitute for two or more 60 terminal ciphers to serving merely to complete the field after the carding of a number of one, two, three or four figures, secures an increase of approximately eleven per cent in the working capacity of a tabulating card 65 code, by using the left-hand columns en-

tirely independent of the right-hand columns, with several distinct advantages besides the mere increase in capacity.

The use of smaller (prefix) series auxiliary to the main series of natural numbers is perfectly unobjectionable from a card tabulating standpoint, and such series may sometimes be employed with advantage in heavy work, even when the total capacity thus secured is much in excess of the actual requirement, since in the new method it results in a marked increase of preferred numbers for writing, carding and sorting.

With the increased capacity (generally speaking about eleven percent) and especially with its very easy extension into six figures or more, obviously each group would utilize its one, two and three-figure numbers before going at all extensively into four figures or more.

Thus, the Import Schedule, with only 83 classes in group 7, which are now scattered from 70114 to 79361, uniformly five-figured and typically requiring five runs for each class (card), might easily be coded entirely 90 in small numbers, somewhat as follows:

7	1 one-figure number, punched 2 holes, sorted 2 runs
70 to 79	10 two-figure, numbers, punched 3 holes, sorted 3 runs
79	
799 to 771	72 three-figure numbers (with 28 unused three-figure numbers) punched with 4 holes but sorted in 3 runs, since the X in the fourth column would "looksee" as soon as the third sorting was accomplished provided there were no four-figure numbers in group 7.

Every other group would have available the same quota of best numbers, with a grand total as stated elsewhere.

Because of the substitutional function of X in the second, third and fourth columns of the field, the postoffice code has theoretically three grades of preferred numbers distributed and preferred as follows (omitting for simplicity of presentation the consideration of the special prefix series with initial 0 and X):

9 firsts, 10,000 to 90,000, punched 1x --- etc. and sorted twice
81 seconds, 11,000 to 99,000, punched 11x --- etc. and sorted 3 times
810 thirds, 10,100 to 99,900, punched 101x --- etc. and sorted 4 times

all of these preferred numbers being five-figured in writing.

The system wholly ignores the thousands of smaller numbers, whereas the left-hand system utilizes them in four classes of preference (comparably excluding the 0 and X 120 series), thus:

9 firsts, 1 to 9 inclusive, punched 1x --- etc., sorting in 2 runs
90 seconds, 10 to 19, 90 to 99, punched 10x --- etc., sorting in 3 runs
900 thirds, 100 to 199, 900 to 999, punched 100x --- etc., sorting in 4 runs
9000 fourths, 1000 to 1999, 9000 to 9999, punched 1000x --- etc., theoretically sorting in 5 runs, but in practice more often sorting in only 4 runs.

It may be noted that all of these left-hand preferences are preferred in writing over any corresponding preferences in the right- 130

hand method, and that there is a very heavy fourth preference in the former which is entirely lacking in the latter.

After making all allowances for the adaptation of numerical groups to commodity groups, there would be an economy over the present method in the number of preferred classes, and in the nature of their preferences, with a still greater economy in the handling 10 of cards punched for those preferred, more active classes.

Still further, the preferred numbers would be distributed rather evenly throughout the schedule instead of being confined as now 15 to group 0 (in Foreign Trade Schedules), where they cannot possibly be used to the best advantage.

The 0 series of the postoffice code, like its X series, respectively illustrated by 01000, 20 Portsmouth, New Hampshire, and X1000, Honolulu, is "an independent series of unit numbers" of four digits each, with a special prefix symbol (well known in the coding art) employed in this case to bring units under units and thousands under thousands, 25 and it is not merely an attempt to use the natural numbers of the regular series beginning with 1. These prefixes must be written as well as punched and sorted.

30 In the foreign trade codes, on the other hand, (some of) the smaller numbers are frankly used, being written simply 10, 14, 19, for example, in the export code, and 101, 102, 191, etc. in the import code. It is only in 35 carding and sorting them that they are given the prefatory ciphers (0010, 00101, etc.), and these ciphers clearly arise out of the technical carding and sorting necessities of the prior art, with its handicap of right-hand lineup 40 in order to bring units under units.

In such carefully considered codes as those for postoffices and the foreign trades, the advantages thus typically inherent in small numbers cannot be fully realized. The conventional requirement of units under units handicaps the coding of any large series of offices or commodities because of the necessity of preceding the small number with one or more ciphers in punching, whether or not the 45 ciphers are recognized as part of the written code, and because the left-hand ciphers cannot be easily skipped, either in carding or in sorting, as the right-hand ciphers may be, if desired.

50 Because of this, all large codes either ignore the small numbers or throw them into a single group by themselves, to the exclusion of other groups. This results in an embarrassment of wealth of small numbers in the 0 group, practically necessitating a great waste of the best numbers, since group 0 usually consists of only a few hundred classes of commodities, while there are many hundreds of relatively small numbers in 55 such code systems available for assignment,

and preferably to active or otherwise important classes.

As a further result, the other groups in such coding are precluded from participation in small-number assignment and are handicapped by an undesirable proportion of large numbers, to-wit, 100 percent. This typical waste of best numbers may be stated more specifically. Thus, the export code is officially indexed as follows:

Group 0, classes 10 to 999 (carded and sorted 000 to 0999)
Group 1, classes 101 to 1779
Group 9, classes 9111 to 9999

and the import code:

Group 0, classes 101 to 9939 (carded and sorted 0001 to 09939)
Group 1, classes 10311 to 17801
Group 9, classes 90101 to 99999

But group 0 of the export code has only 138 classes and group 0 of the import code has only 289 classes, so that 861 small numbers (86%) of the one group and 9,710 small numbers (97%) of the other are wholly unused.

In contradistinction the left-hand codes would be something like this:

Group 1, class 1 with 1 best number,
classes 10 to 19 with 10 second best,
classes 100 to 199 with 100 third best,
classes 1000 to 1999 with 1000 next best,
classes 10000 to 19999

etc.

Similarly with the eight other regularly-numbered groups:

Group would contain class 0 (if desired)
classes 00 (or 01) to 09
classes 000 (or 001) to 099
classes 0000 (or 0001) to 0999

etc.

In all this left-hand system of coding, however extended the number of figures, there is 100 a visual continuity of numbers assigned in any group different from the ordinary numerical continuity, but perhaps even more valuable; and however extended the number of columns in a carded group, there would be 105 a mechanical separation of main groups in the first running, a mechanical separation of sections in each group in the second running, etc., so that both visually and mechanically there would be a practical continuity or 110 consecutiveness of the numbers of any group, or section, or sub-section, etc., each by itself, which would also permit the insertion of new numbers in their appropriate classification, quite beyond any economical practice of the 115 prior art. To more concretely and tangibly illustrate my invention, an example of how the invention can actually be applied will be given.

Referring first to Figures 1 and 2 a brief 120 description of the operation of a card sorting machine will be given. The machine shown is merely illustrative of any one of a number of machines which may be used in carrying out my invention. The illustrative 125 machine is of the type used by the United States Census Bureau and shown and described in the patent to La Boiteaux No. 1,048,137 issued February 19, 1924, so that a detailed description is not here necessary.

130

The cards 21 to be sorted are stacked in a hopper 22 and are advanced from the bottom of the stack by any suitable feeding means such as a reciprocating plate 23 and fed to the rollers 24 and guides 25. A spring pressed contact finger 26 is adjustably secured to a transverse plate 27, the contact being adapted to slide over one of the vertical columns of the card as the card passes beneath it. The function of the machine is to sort the cards 21 into the pockets 28 corresponding to the perforations of the card in the column being sensed. A plurality of guide leaves 29 pivoted or bent around a fixed support 31 have their posterior ends connected by strips 32 to the top of the pockets 28. The leaves 29 are arranged to be successively raised by a cam 33 which is moved longitudinally to the right once during each cycle of the machine. This cam 33 is driven through an oscillating ratchet sector 34 which in turn receives oscillatory movement through a lost motion connection with the follower arm 35, the roller of which engages the slot of the cam 36. The cam 36 rotates at a constant speed, making one revolution for each cycle of the machine.

When the spring contact finger 26 passes through a perforation in the card, it swings the bell crank 37 counter-clockwise, thus releasing a dog 38 which is spring pressed so as to engage the ratchet sector 34 and is normally restrained by engagement with the lower end of the vertical arm of the bell crank 37. It will therefore be apparent that the position at which the ratchet sector is arrested will depend upon the position of the perforation in the card passing beneath the spring contact finger. The cam 33 will also be limited in its longitudinal travel at a position corresponding with the position of the perforation in the card. The leaves 29 will then be so positioned vertically relative to the last pair of rollers 24 that the card will be inserted between that particular pair of adjacent leaves which define a longitudinal path or guideway leading to the corresponding pocket 28. Once thus introduced between a pair of adjacent leaves, the card is progressed along by the pusher arms 39 on an endless belt, until it drops into the pocket.

Although but a brief description of this machine has been given and many details have been omitted, it will be apparent that the position (from the forward edge of the card) of the perforation will control the operation of the machine to carry the particular record card to the pocket which corresponds to the perforation in its column or file being sensed. It should also be noted from Figure 2, that the spring contact member 26 may be adjustably positioned so as to adapt it to sense the perforations in any desired vertical column of the cards.

65 In Figure 3 I have shown a tabulating card

21 which is illustrative of the kind used in the post office money order auditing department. This card has columns in which the various details of information such as the fee, serial number, issuing office number and file number may be recorded by suitable punching. To illustrate one characteristic auditing operation, cards similar to that here shown representing the money orders cashed at a particular office must be sorted out according to the issuing office number. In Figures 4 to 13, only the portions of the cards which include the issuing office field are shown. Perforations are represented by a large black dot. The card in Figure 3 is punched to indicate that its corresponding money order was issued by office No. 1, which we shall assume is the Chicago Post Office.

70 It will be seen that the perforations are made by beginning the punching at the left hand column of the field, irrespective of the number of digits in the office designation. The "1" is punched in the extreme left column and another perforation is made in the "X" position in the column second from the left. This is in contradistinction to the prior art method of punching where punchings would be made for all of the zeros before the first substantial digit (as indicated by the check marks on the drawings), that is, the issuing office designated "1"—if such designation had been used in the old system of designations—would have been punched 00001; whereas by my method, the card will be punched 1x, thus saving three punching operations.

75 The table below gives exemplary designations for post offices in different cities which will be used concretely to illustrate how my invention may be carried out. For the purposes of this illustration, it will be assumed that there are 2400 cards to be sorted, 800 in the Chicago (1) group or class punched 1x, 800 in the New York (2) group punched 2x, etc. The cards of course are not arranged 80 in groups but are shuffled indiscriminately.

Illustrative example

No. of cards	Designation perforations		City	Shown in Fig. No.
	New method	Old method		
800	1X	00001	Chicago, Ill.	3
800	2X	00002	New York, N. Y.	4
300	3X	00003	Philadelphia, Pa.	5
230	4X	00004	Boston, Mass.	6
190	5X	00005	San Francisco, Calif.	7
40	21X	00021	Buffalo, N. Y.	8
26	22X	00022	Ithaca, N. Y.	9
10	224X	00224	Hackensack, N. Y.	10
2	2241X	02241	Binghamton, N. Y.	11
1	22415	22415	New Rochelle, N. Y.	12
1	22417	22417	New Salem, N. Y.	13
Total... 2,400				

115 Assuming now that an office, say Detroit, has the above numbers of cards representing 120

money orders cashed from the particular cities as tabulated above, according to the old method of sorting generally employed, the cards would first be sorted according to the left hand column of the issuing office field. It will be apparent that the determining perforations (according to the prior art as I have indicated by check marks on the drawings) of each card occurs in the right hand file of this field and it will therefore be necessary to run all of the cards through the sorting machine five times. Since there are 2,400 cards, the machine necessarily will, in order to complete the sorting operation, virtually handle 12,000 cards, that is, handle each one of the 2,400 cards five times.

However, with the cards punched according to my invention and the sorting machine operated in accordance therewith, the operation will be as follows:

In the first sorting operation the contact finger will be set so that the machine will sort the cards according to the perforations of the left hand file of the issuing office field. Of course all of the cards will have to be passed through the machine in this first operation. It will be understood that for the second card sorting operation the finger is set to sense the second file from the left; for the third sorting operation it is set to sense perforation in the third file from the left; and so on progressively.

In the second sorting operation the cards each having two punches or more have to be sorted. Since a card punched for even a single digit has to have two perforations, that is, a number perforation and an X perforation, this means that all of the cards have to be put through the second sorting operation. However, in the second sorting operation the cards which have only two punches, namely: 1X, 2X, 3X, 4X and 5X will be separated from the remaining cards and finally sorted. Therefore after the second sorting operation the two punch-cards need not again be handled by the sorting machine.

In the third sorting operation all cards having three or more punches are sorted, but the cards having only three perforations namely: 21X and 22X will be separated from the remaining cards and finally sorted. Similarly therefore the three punch-cards need not again be sorted.

In the fourth punching operation the remaining cards, that is cards having four or more perforations are handled and the four punch-cards (in this instance cards perforated 224X) are separated from the other cards and finally sorted so that they do not have to be handled again.

The fifth sorting operation handles the remaining cards, which are cards having five perforations namely: 2241X, 22415 and 22417. The fifth sorting operation separates

all of these five punch-cards and finally sorts them.

The total number of cards handled in each sorting operation is as follows:

First sorting operation	2,400	70
Second sorting operation	2,400	
Third sorting operation	80	
Fourth sorting operation	14	
Fifth sorting operation	4	76

Total for the five operations 4,898

The total number of cards handled the old way would be 2400 times 5 or 12,000. This huge saving is not exaggerated. It is due in part to the fact that the cities that issue the greater number of money orders can be assigned the smallest designation numbers so that the cards punched with these small numbers are completely sorted in the second sorting operation (if they have one digit designation, but at the end of the third sorting operation if they have two digit designations). In the old method each card had to be run through the sorting machine five times regardless of the number of digits in the designation.

As previously pointed out, a great saving can sometimes be effected by looking to see if all the cards removed from one pocket have a perforation in the "X" position in the file according to the perforations of which the next sorting operation is to be made. Thus in the illustrative example all of the cards in the "1", "3", "4" and "5" pockets at the end of the first sorting operation would have a perforation in the "X" position in the second file. This fact may be readily noted by the operator by aligning the stack of cards and running a wire through the "X" perforations in the second file or by merely holding the cards in alignment and observing that all of the cards are punched in the "X" position in their second files. This method of eliminating part of the sorting operation is well known and can be utilized in sorting according to the old method although it obviously has greater advantages when employed with my invention.

My invention, as applied to tabulating card work relieves the art of the units-under-units handicap of small numbers and makes mechanically feasible and practicable the distribution of the desirable numbers of a large code among the accepted classification groups with a fair approach of equality, thereby decreasing the mental and physical work involved in the handling of punched cards.

Advantages corresponding in nature to those hereinbefore set forth in tabulating card work will also be easily secured in the generically related work of handling documents and communications which are similarly handicapped by a right-hand lineup in coding or in operation.

In all this punched-card work, the card is merely a convenient tool or automatic means for controlling the operation of the sorting machine, which operation in turn is merely the intermediate end in view preparatory to the final analytical tabulation of the quantitative data.

In another closely related aspect of the work, the documents from which the cards have been punched sometimes need sorting into the same groupings as the cards to be filed for convenient reference, while in other lines the documents are sorted for filing in classified groups or in serial number order, or both, without having had their data transferred to punched cards.

This sorting of documents may be accomplished either as a result of perforations formed in the documents themselves or by the operation of mechanism controlled directly by keys actuated in accordance with the numbers of the coded documents, and in this aspect the general advantages of an equal distribution of the smaller numbers of the natural series, are essentially the same as when applied to the punched-card work.

In still other lines which, for the purposes of this specification, may be considered generically similar, the mechanical setup or controlling means is neither for the purpose of tabulating or filing, but rather, as in telephone work, to establish the necessary sorting or routing of communications between senders and receivers, the latter being grouped according to locality into exchanges or the like and then individually numbered or coded in a list which frequently embraces thousands of names.

For the purpose of this specification, the names are analogous to classes in which cards are sorted for tabulation or to pockets into which documents are sorted for filing, in that the communications are classified or sorted and routed into receiving devices numbered according to the subscribers on the codified list.

It would seem to make no difference in the essence of the method whether the routing be determined by the senders in the automatic system, or by the operators at the central office in the manual system. The general advantages of the left-hand lineup coding are inherent in either system. The connections may be established more quickly and with less switching because of the greater number of small-number assignments, and the general public will more readily note and more easily remember the small numbers, with less liability to error in dialing or otherwise transmitting the code number for the controlling of the connections.

The punched card embodies a separate, permanent and tangible setup which may be employed to control the sorting at any convenient subsequent time, and the card punched

by my method may be used in the ordinary way in connection with the ordinary card-sorting machines, so that while the process of punching the card according to the novel grouping constitutes a method by itself, in the narrow sense, the broader process consists in the novel making of the tool and then using it to accomplish the finally useful purpose.

The sorting of documents and the routing of telephone communications, on the other hand, do not necessarily involve the making of any permanent setup, but do require the co-operation of more or less specially constructed devices, which receive and transmit the documents or the communications to their novelly-grouped and novelly-selected resting places. The temporary physical setup is thus promptly followed by and merged with the actual distribution in a single process for each document or communication which corresponds to the broader process of making the card and using it, and in each case the advantages of the left-hand lineup are substantially the same.

Having thus described my invention, what I claim as new and desire to secure by Letters Patent of the United States is:

In a tabulating card sorting system, a plurality of cards having fields arranged in files and perforated to designate numerical values ranging from one to three or more digits, adapted to be sorted by a machine for sorting the cards into ultimate classes, the total number of which runs into three or more digits, the sorting machine having a sensing element for progressively traversing the files of the fields of the respective cards for sorting the cards in response to the perforations therein, each card being perforated, beginning with the first file sensed, for only the first significant digit and the digits to the right thereof in its corresponding numerical value with an x perforation in the file succeeding the file containing the last coded digit to the right.

In witness whereof, I hereunto subscribe my name this 5th day of April, 1924.

CHARLES H. TALLMADGE.

CERTIFICATE OF CORRECTION.

Patent No. 1,768,806.

Granted July 1, 1930, to

CHARLES H. TALLMADGE.

It is hereby certified that error appears in the printed specification of the above numbered patent requiring correction as follows: Page 5, line 95, after the word "Group" insert the capital letter O; and that the said Letters Patent should be read with this correction therein that the same may conform to the record of the case in the Patent Office.

Signed and sealed this 26th day of August, A. D. 1930.

(Seal)

**M. J. Moore,
Acting Commissioner of Patents.**
